BOX TOE HEATER

Ross H. Lowe, Hanover, Pa., assignor to The Hanover Shoe, Inc., Hanover, Pa., a corporation of Pennsylvania

Application October 21, 1939, Serial No. 300,636

2 Claims. (Cl. 12—1)

My invention relates to a box toe heater.

The object of this invention is to provide a simple means for heating and steaming the stiffener used in making box toes on shoes.

The purpose is to provide means for confining the steam or vapor employed in the operation within certain limited area beyond the toe of the last, as the desideratum is to prevent the moisture from the steam or vapor from reaching the exterior of the upper or passing beyond the surface required to be heated.

In the accompanying drawing:

Fig. 1 is a view in perspective of a form of machine showing a last and upper in dotted lines;

Fig. 2 is a vertical sectional view showing parts in full and parts in dotted lines;

Fig. 3 is a fragmentary plan view;

Fig. 4 is an enlarged sectional view through the upper end of the machine, showing the toe and stiffener in dotted lines; and

Fig. 5 shows a slightly modified form of the shield with the steam or vapor vents on the forward side instead of on the upper surface of the shield.

The numeral 1 represents a tank of suitable size and proportions mounted on a standard 2 adapted to be supported on the floor.

An adjustable rest 3 for the shoe is pivotally attached on opposite sides of the upper end of the tank as a convenient means of support. This rest may be moved to different positions to support the shoe and last to suit the convenience of the operator.

The upper 4 is shown in dotted lines in Figs. 1 and 2 and supported on the rest 3. The upper is drawn more or less tightly over the last 5, and preferably temporarily fastened by one or two tacks at the heel (not shown) in the customary manner.

A shield 6 extends upwardly from the inverted U-shaped pipe 7, and this is preferably bowed outwardly at the center as shown in the drawing to correspond with the curvature of the shield 6, which latter is made to approximately conform to the shape of the toe of the last.

Perforations 8 are formed at suitable intervals in the bowed portion of the pipe 7, through which the steam or vapor issues upwardly, as indicated by the arrows in Fig. 4 directly against the under-side of the box toe stiffener 9, and the toe-piece 10 of the upper which extends thereabove.

The pipe 7 is preferably removable from the tank through holes 11 in the top of the tank.

One or more holes 12 on the lower side of the pipe 7 are provided for the escape of condensation.

As a slight modification the perforations 8 might be in the forward side of the shield 6 as

viewed in Fig. 5, it being understood that the object is to concentrate the application of heat so far as possible to the area substantially represented by the space 14 forward of the shield 6 and beneath the projecting forward end of the stiffener and toe-piece as illustrated.

The shield 6 virtually has the function of a valve for insuring this confinement and concentration to the surface desired and preventing it from going elsewhere.

For this reason the shield is so placed that it extends between the canvas lining 15 and the stiffener 9, as shown in Figs. 2 and 4.

If steam is used, it is supplied through the pipe 16, whereas if vapor is preferred, it is supplied through the pipe 17, in which event it is passed through a body of water in the lower end of the tank, and thence into the upper portion of the tank and out through the perforations 8.

When steam is employed, the condensation passes out through pipe 17, and when vapor is used the level of the water is determined by the pipe 16 which serves to maintain the water level.

It has been found by this simple mechanism the steam or vapor is effectually confined to the intended surface, and the arrangement of parts is such that the process is carried out with facility.

After the steaming and heating has been completed, the toe-piece and stiffener are drawn down around and beneath the toe of the last 5 and temporarily fastened usually by a toe wire (not shown).

It will be apparent that the projecting end of the stiffener and toe-piece virtually forms a hood, which in cooperation with the shield receives, arrests, and disperses the steam or vapor beneath the predetermined surface intended to be heated and softened.

I claim:

1. A box toe heater including a steam or vapor tank, a pipe communicating with said tank and having perforations on its upper surface, and an approximately vertical shield connected with the pipe in position to confine the discharged steam or vapor to a predetermined area to be heated.

2. In a box toe heater the combination of a steam or vapor tank, means for supplying steam or vapor thereto, an inverted U-shaped pipe detachably connected to said tank and communicating therewith, apertures in the upper side of said inverted U-shaped pipe, and a shield secured to one side of said inverted U-shaped pipe directing steam or vapor from the apertures in a predetermined direction.

ROSS H. LOWE.
